UNITED STATES PATENT OFFICE.

BEN F. CLARK, OF WICHITA, KANSAS.

NEST.

1,152,706.

Specification of Letters Patent.

Patented Sept. 7, 1915.

Application filed June 9, 1914. Serial No. 844,050.

To all whom it may concern:

Be it known that I, BEN F. CLARK, a citizen of the United States, residing at Wichita, in the county of Sedgwick and State of Kansas, have invented a new and useful Nest, of which the following is a specification.

This invention relates to improvements in nests of that class which are used for the segregation of laying hens.

An object of the present invention is to provide a nest with novel branding means and actuating means therefor.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings accompanying this specification and forming a part thereof, the preferred embodiment of my invention is illustrated.

In said drawings:—Figure 1 is a view in vertical section of the improved nest. Fig. 2 is a cross sectional view taken on the line 2—2 of Fig. 1. Fig. 3 is a view of a detail.

Referring to the drawings in which similar reference numerals designate corresponding parts throughout the several views, the casing or frame is provided with the vertical guides 5 extending along the side edges of the front entrance opening or doorway 7. A door 6 is slideable vertically within the guides 5 to close and open the entrance opening 7 leading to the interior of the casing. Suitable stops 7' are carried by the lower ends of the guides to prevent the door from being lowered excessively.

The bottom 8 of the casing has an opening 9 in which the nest tray 10 is disposed. The forward end of the nest tray is provided with an outstanding flange 11 which rests upon the bottom 8 and is so connected thereto, as at 12, as to enable the rear or free end of the nest tray to swing vertically. A lever 13 is fulcrumed to a bracket or hanger 15 depending from the top of the casing adjacent the rear wall or back of the casing, and the lever is provided with a relatively short rearwardly projecting arm and with a relatively long forwardly projecting

arm. The rear arm of the lever 13 is disposed above the rear or free end of the nest tray 10, and the rear arm or end of the lever and the rear or free end of the nest tray are connected by an upright bail-shaped link 14. The forward arm of the lever is provided with a plurality of apertures 16 with which is adjustably engaged a weight 17 for normally maintaining the tray 10 in a raised position.

The front wall of the receptacle is provided with an inner shelf 18 which is disposed above the forward end of the nest tray 10 and supports the reservoir or tank 19 of the branding device. The reservoir 19 includes a cover 20 having a removable cap 21 to permit the tank to be filled from time to time. The cover of the reservoir is provided with a slot 22 through which a link 23 extends, the upper end of the link 23 being pivotally connected to the forward end or arm of the lever 13 and the lower end of the link 23 being pivotally connected to a dispensing trough 24 carried by the reservoir. The dispensing trough 24 extends through an opening 25 provided in the rear wall of the reservoir above the level of the branding liquid L within the reservoir, and the trough 24 is pivotally connected to the rear wall of the reservoir, as at 26, and the rear end of the trough projects from the rear side or wall of the reservoir, while the other or forward end of the dispensing trough is swingable within the reservoir to positions below and above the liquid level. The link 23 is pivotally engaged to the inner or forward end of the trough 24, whereby when the nest tray 10 is depressed to swing the forward arm of the lever 13 upwardly, the trough 24 will be swung beyond the horizontal position to discharge the contents of the trough. The trough 24 has the side flanges 27 and has its forward end closed, as at 28, while the rear or protruding end of the trough is open, and overhangs the nest tray 10. The sides or flanges 27 of the trough are provided with apertures 29 adjacent the forward end 28 and bottom of the trough, for enabling the branding liquid to flow readily into the dispensing trough, when the forward end of the dispensing trough is swung downwardly, as seen in Fig. 1.

Particular attention is directed to the fact that the weight 17 being adjustable along the long arm of the lever 13, may be adjusted for controlling the velocity at which the

nest tray 10 swings downwardly, when the hen steps thereon. This is also of importance in connection with the branding device, and especially in connection with the 5 apertures 29 provided in the sides of the trough 24 adjacent its bottom and forward end. Thus, when the weight 17 is adjusted to enable the nest tray to swing downwardly quickly, when the hen steps thereon, the 10 trough 24 will be swung upwardly quickly, whereby almost the entire quantity of branding liquid contained in the trough will be elevated thereby and discharged onto the hen. However, when the weight 17 is adjusted 15 so that the nest tray swings downwardly slowly, when the hen steps thereon, the trough 24 will be moved upwardly slowly, and as a result a portion of the branding fluid contained in the trough 24 will run 20 back into the reservoir through the apertures 29, and as a result a less quantity of the branding fluid or liquid will be discharged onto the hen. Thus, by adjusting the weight 17, the speed of actuation of the 25 device may be controlled, and furthermore, the amount of branding liquid discharged is also regulated correspondingly.

In order to trap the hen within the casing and to exclude other fowls therefrom while 30 the nest is occupied, a device is employed for normally holding the door 6 in raised or open position and for releasing the door when the nest is occupied, to enable the door to gravitate or drop to closed position. 35 Thus, a pair of guides or brackets 30 are secured to the casing or frame at the side and upper edges of the entrance opening 7, and a pair of latch rods 31 are pivotally connected, as at 31', to the nest tray adjacent the side edges and rear end thereof, the latch rods 31 passing slidably through the guides 30 and having their forward or free ends 30' arranged to project or engage under the lower edge of the door 6 when the 40 door is raised, as seen in Fig. 1, and when the rear end of the nest tray 10 is raised. Thus, to set the trap, the door 6 is first raised and the rear end of the nest tray 10 being raised will cause the forward or projecting ends 30' of the latch rods 31 to project under the door for holding the door raised until the nest is occupied, which will cause the nest to gravitate or swing downwardly for retracting the latch rods 31 from 45 under the door, so that the door will close for the intended purposes.

The casing or frame 1 is preferably provided with a removable cover or lid 34 which is dove-tailed into the top of the casing, as at 35, to enable the cover 34 to be slid open laterally. The cover or closure 34 may be held in closed position by means of pins 37 or other suitable securing means, and the cover 34 is preferably provided with 50 a suitable handle 36.

A latch 32 is carried by the front wall of the casing 4 at the upper edge of the entrance opening 7, and is engageable under the door 6 when it is desired to hold the door raised for allowing the free entrance 70 and exit of the fowls.

In use, a suitable branding liquid L is poured into the receptacle or tank 19, the liquid containing suitable pigments or dyes adapted for marking or branding the hen 75 which occupies the nest, in order that the hen may be distinguished from the others.

When the nest tray 10 is occupied, it will be swung downwardly under the weight of the hen, which will swing the lever 13 so as 80 to raise or elevate the dispensing trough 24, and which will result in a small quantity of the branding liquid L being discharged from the dispensing trough 24 onto the hen for the intended purpose. When the door 6 85 is held open, as illustrated in Fig. 1, prior to the entrance of the hen into the casing, the door 6 will be automatically released as soon as the nest is occupied, for confining the hen within the casing, and for excluding 90 other fowls, in order that the laying hen may be caught.

An inwardly projecting stop 33 is preferably carried by the casing 4, for limiting the upward movement of the forward arm of 95 the lever 13.

Having thus fully described my invention, what I claim is:—

1. In a device of the character described, a frame, a nest tray having its forward end 100 connected to the frame to enable the rear end to swing vertically, a liquid reservoir carried by the frame above the forward end of the nest tray, a dispensing trough pivotally connected to and having one end projecting from the rear side of the reservoir, the other end of the trough being swingable within the reservoir below and above the liquid level, the sides of the trough having apertures adjacent the last mentioned end 105 and the bottom of the trough, a lever fulcrumed to the frame above the nest tray and reservoir and having relatively short and long arms projecting rearwardly and forwardly, links connecting the short arm of the lever and rear end of the nest tray and the long arm of the lever and last mentioned end of the trough, whereby when the nest tray is swung downwardly, the dispensing trough will be swung upwardly to discharging position, and an adjustable weight carried by the long arm of the lever. 115

2. In a device of the character described, a frame, a nest tray carried thereby and movable vertically, a liquid reservoir carried by the frame above the nest tray, a dispensing trough pivotally connected to and having one end portion projecting from the reservoir, the other end of the trough being swingable within the reservoir below and 120

above the liquid level, the sides of the trough having apertures therein adjacent the last mentioned end and the bottom of the trough, and means operatively connecting the nest tray and dispensing trough whereby when the nest tray is moved downwardly, the dispensing trough will be swung upwardly to discharging position, the said means including adjustable means for controlling the

velocity at which the nest moves downwardly.

In testimony that I claim the foregoing as my own, I have hereto affixed my signature in the presence of two witnesses.

BEN F. CLARK.
